UNITED STATES PATENT OFFICE.

ADOLPH T. SMITH, OF NEW YORK, N. Y.

ELECTRIC GAS-BURNER.

SPECIFICATION forming part of Letters Patent No. 349,533, dated September 21, 1886.

Application filed February 18, 1886. Serial No. 192,468. (No model.)

To all whom it may concern:

Be it known that I, ADOLPH T. SMITH, a citizen of the United States, residing at New York, in the county and State of New York, 5 have invented new and useful Improvements in Electric Gas-Burners, of which the following is a specification.

This invention consists in the construction of the insulated burner, substantially as here-
to inatter specified.

In the accompanying drawings, Figure 1 is a side elevation, partly in section, of an electric gas-burner containing my invention. Fig. 2 is a side elevation, partly in section, of a modification. Fig. 3 is a side elevation, partly in section, of a modification.

Similar letters indicate corresponding parts.

In the drawings, the letter A designates a body, pillar, or gasway of a gas-burner. In 20 the case of electric gas-burners this body or pillar is frequently made of material which is an insulator or non-conductor of electricity. I have found that a good insulating material for this purpose is paper or papier-maché. 25 This substance (paper or papier-maché) is cheap, and can be readily rolled, pressed, formed, or molded into any desired suitable or ornamental form.

To attach the pillar A to a gas-pipe a lining or bushing, B, of metal or other suitable material is attached to the pillar A by means of any suitable adhesive—as, for example, plaster-of-paris; or said bushing can be screwed to the pillar or attached in any other suitable 35 way. By providing the lining or bushing B with a screw-thread, J, the lining or bushing can be screwed onto a gas-pipe.

By providing the pillar or body A with a suitable tip or nipple, C, from which the gas 40 issues, any suitable flame is obtained—as, for example, a bat's-wing flame, or a fish-tail flame, or other desired form of flame.

The tip or nipple C can be made of lava, metal, or other suitable material. The tip can 45 be held in place either by being screwed in or fitted in place in any suitable manner.

The electrode D is attached to the burner in any suitable manner—as, for example, by clamping the same about the body or pillar A, or 50 in any other suitable well-known manner. If the tip C is made of a conductor of electricity—

as, for example, certain kinds of metal—the electric spark can be made to jump from the electrode D into the tip C. The tip C thus serves as one of the electrodes. By attaching 55 a conductor, F, to the tip or electrode C, as seen in Fig. 1, the electricity can be carried off to ignite the gas-jets from other burners.

In case the tip C is made of material which is a non-conductor of electricity—as, for example, lava—an electrode, E, has to be applied. This electrode E may be applied in various ways. For example, in Fig. 2 the electrode E passes through a hole or perforation in the tip C, and passes through the interior of the 55 tip C into contact with a conducting bushing, sleeve, or collar G. The collar G can be attached to the pillar A in any well-known manner—as, for example, by plaster-of-paris or by screwing. By attaching the conductor F to 70 the collar G the electricity can be led off as desired.

The paper or papier-maché pillar or body A can be made of various forms or configurations—as, for example, in Figs. 1 and 2, where 75 the pillar or body is of considerable length.

Another form of pillar A is shown in Fig. 3, where the pillar A is provided with a hollow or socket, into which fits a shank or stem of a head, H. By means of glue, plaster-of-paris, or other adhesive the head H and pillar A can be firmly joined together. The pillar A can rest on a base or support, A', of metal or any other suitable material, or it may be placed directly on the gas-pipe. The tip C 85 can be inserted into the head H in any suitable well-known manner. The electrodes D and E can be attached to the head H in any suitable manner—as, for example, by screws or pins. By inserting between the head H and pillar A 90 a disk or washer, I, of suitable insulating material—as, for example, isinglass, porcelain, glass, or lava—a guard-flange is formed which prevents the spark from jumping from the electrodes into the metal part of the gas-pipe. 95

The paper or papier-maché pillar can be colored or ornamented in any desired manner, or it can be glazed or enameled or provided with a porcelain sleeve, as in a so-called "candle-burner."

To form the pillar the paper or papier-maché is either rolled or wound about a suitable

core, the core being withdrawn after the pillar is formed; or the pillar is formed by pressing the paper or papier-maché in a suitable mold. In case paper is rolled about a core, a suitable adhesive—as, for example, glue—must be applied to the paper to prevent the paper from unwinding.

By applying a coat of glazing or a sleeve of porcelain or other non-combustible material to the danger of the paper or papier-maché pillar becoming ignited is averted.

I have found that in the case of gas-burners which were heretofore provided with asbestos bodies the asbestos crumbles or disintegrates under the influence of the heat. This does not occur in the case of my burners provided with a paper or papier-maché body. With regard to burners provided with lava bodies or insulators, the disadvantage is, that the lava has first to be turned or formed and then perforated or drilled, and finally baked to bring it into a condition proper for use in gas-burners. This proceeding is quite different from the manufacture of my burner, in which the paper or papier-maché provided with an adhesive is simply rolled or molded, and upon drying said paper or papier-maché body is at once ready for use.

What I claim as new, and desire to secure 30 by Letters Patent, is—

1. The pillar or gasway A of a gas-burner, made of paper or papier-maché, substantially as set forth.

2. An insulated gas-burner having its insulating-section constructed of or from paper or papier-maché, substantially as and for the purpose specified.

3. The combination, with a paper or papier-maché pillar or gasway, A, of a conductor, D, and a metallic gas-tip, substantially as set forth.

4. The combination, with a paper or papier-maché pillar or gasway, A, of a conductor, D, and a lava gas-tip, substantially as set forth.

5. The pillar or gasway A, made from paper or papier-maché and provided with a screw-thread, J, in combination with a conductor, D, substantially as set forth.

6. The pillar or gasway A, made from paper or papier-maché, provided with an electrode or electrodes, and provided with a guard-flange, I, at a point below the electrodes, substantially as set forth.

In testimony whereof I have hereunto set my hand and seal in the presence of two subscribing witnesses.

ADOLPH T. SMITH. [L. S.]
